US009993059B2

(12) **United States Patent**
Langdon et al.

(10) **Patent No.:** **US 9,993,059 B2**
(45) **Date of Patent:** **Jun. 12, 2018**

(54) **ROLLER APPLICATOR**

(71) **Applicant:** **HCT GROUP HOLDINGS LIMITED**, Central (HK)

(72) **Inventors:** **Megan Rene Langdon**, Los Angeles, CA (US); **Kamaal Washington**, Los Angeles, CA (US); **Denis Pierre Maurin**, Los Angeles, CA (US)

(73) **Assignee:** **HCT GROUP HOLDINGS LIMITED**, Hong Kong (HK)

(*) **Notice:** Subject to any disclaimer, the term of this patent is extended or adjusted under 35 U.S.C. 154(b) by 34 days.

(21) **Appl. No.:** **15/204,116**

(22) **Filed:** **Jul. 7, 2016**

(65) **Prior Publication Data**

US 2017/0007000 A1 Jan. 12, 2017

Related U.S. Application Data

(60) Provisional application No. 62/244,379, filed on Oct. 21, 2015, provisional application No. 62/191,228, filed on Jul. 10, 2015.

(57) **ABSTRACT**

Illustrative applicators include a roller controllably coupled to a reservoir by a wicking agent such as a felt applicator insert. A cap for the applicator is also provided. The action of the cap being placed over the roller brings the roller into contact with the wicking agent, applying product contained in the reservoir to the roller. Removing the cap causes the roller to move out of contact with the wicking agent, allowing a quantity of product applied to the roller while the cap is on the applicator to be used.

ROLLER APPLICATOR

CROSS REFERENCE TO RELATED APPLICATIONS

The present patent application claims the benefit of and priority to U.S. Provisional Patent Application No. 62/244,379, filed Oct. 21, 2015, and U.S. Provisional Patent Application No. 62/191,228, filed Jul. 10, 2015, each titled ROLLER APPLICATOR, the disclosures of which are incorporated herein by reference.

FIELD

The present application relates to the field of apparatuses for applying cosmetic products.

BACKGROUND

There are numerous applicators for cosmetic products available. Some such applicators include a reservoir for holding a product to be applied, and a delivery portion for applying product as needed by the user. New and alternative approaches to such applicators are desired.

Overview

In an illustrative example, an applicator for a cosmetic product is provided including a cap, and a body, the body comprising a roller, an applicator insert to hold the roller, a collar configured for mating with the cap, a spring coupling the applicator insert to the collar, a portion for holding product, and a wicking agent. The roller, applicator insert, collar, spring, portion for holding product, and wicking agent are sized and configured to define a first configuration when the cap is applied and engaged to the collar in which the spring is in a compressed state such that the applicator insert is moved to a first juxtaposition and the roller is brought adjacent to or in contact with the wicking agent to deliver product to the roller, and a second configuration when the cap is not applied in which the spring is in an extended state such that the applicator insert is moved to a second juxtaposition and the roller is separated from the wicking agent.

In another example, in the second configuration, the roller being separated from the wicking agent limits a quantity of product that may be applied without replacing the cap and effecting the first configuration.

In another example, the roller is a ball.

In another example, the applicator insert includes a recess configured to receive the ball, and a ridge configured to retain the ball within the recess, the recess and ridge configured to retain the ball while allowing the ball to rotate freely.

In another example, the roller is a wheel.

In a further example, the applicator insert includes a slot configured to receive the wheel, and a pin configured to retain the wheel within the slot while allowing the wheel to rotate freely.

In another illustrative example, an applicator for a cosmetic product comprises a reservoir for holding the cosmetic product, a collar disposed with an opening of the reservoir, a spring disposed within the collar, an applicator insert having a first end disposed within the spring and extending into the collar, a roller movably fixed to a second end of the applicator insert, an elongate wicking agent disposed within the reservoir and extending through the collar, the spring,

2

and into the applicator insert, and a cap configured for mating with the collar, wherein the reservoir, collar, spring, applicator insert, roller, wicking agent, and cap are configured such that when the cap is engaged with the collar, the cap moves the applicator insert toward the reservoir, thereby compressing the spring and moving the roller into contact with the wicking agent, allowing the cosmetic product to move from the reservoir, through the wicking agent, and into contact with the roller, and when the cap is removed from the collar, the spring relaxes into an extended position, moving the applicator insert away from the reservoir and moving the roller out of contact with the wicking agent.

In another example, the roller is configured to dispense a limited amount of the cosmetic product as the roller is moved against a surface, wherein the limited amount is limited to product in contact with the roller when the cap was removed.

In another example, the roller is configured to receive an additional amount of cosmetic product when the cap is engaged with the collar, moving the roller into contact with the wicking agent.

In another example, the cap has internal ridges that engage ridges on the applicator insert.

In another example, the wicking agent is fixed relative to the reservoir.

In another example, the roller is a ball.

In another example, the roller is a wheel.

In another example, the roller is absorbent.

In another example, the roller is non-absorbent.

In another example, the roller includes one or more dimples in a surface thereof.

In another example, the roller includes a flocking material on a surface thereof.

In another illustrative example, a method of applying a cosmetic product comprises loading cosmetic product onto a roller by placing a cap onto a collar of a cosmetic container thereby engaging the roller with a wicking agent, the cosmetic container including a reservoir for holding the cosmetic product, the collar disposed with an opening of the reservoir, a spring disposed within the collar, an applicator insert having a first end disposed within the spring and extending into the collar, the roller movably fixed to a second end of the applicator insert, the wicking agent disposed within the reservoir and extending through the collar, the spring, and into the applicator insert, and the cap configured for mating with the collar. The method further comprises removing the cap thereby limiting an amount of the cosmetic product loaded onto the roller, and dispensing the limited amount of cosmetic product by rolling the roller onto a user's skin.

In another example, dispensing the limited amount of cosmetic product includes rolling the roller onto skin until the limited amount of product is dispensed, the method further comprising replacing the cap onto the collar to load a second amount of product onto the roller.

In another example, after replacing the cap, the method further comprises removing the cap and dispensing the second amount of product.

This overview is intended to provide an overview of subject matter of the present patent application. It is not intended to provide an exclusive or exhaustive explanation of the invention. The detailed description is included to provide further information about the present patent application.

BRIEF DESCRIPTION OF THE DRAWINGS

In the drawings, which are not necessarily drawn to scale, like numerals may describe similar components in different

views. Like numerals having different letter suffixes may represent different instances of similar components. The drawings illustrate generally, by way of example, but not by way of limitation, various embodiments discussed in the present document.

FIG. 1 shows an applicator having the cap thereon;

FIG. 2 shows the applicator of FIG. 1 without the cap; and

FIG. 3 shows an exploded view of the parts of the applicator of FIGS. 1 and 2.

DETAILED DESCRIPTION

FIG. 1 shows an applicator having a cap thereon. The applicator includes a body 20 and a cap 10. As shown in FIG. 2, the body 20 further includes an applicator portion having a roller 30, which is depicted as a wheel. The roller 30 may be made of an absorbent material such as a felt, or a non-absorbent material such as rubber. The roller 30 may have dimples or ridges, for example, for enhanced product carrying. The roller 30 may instead be a ball, such as a metal, rubber, silicon or other material, again including, in some examples, one or more of dimples, ridges or a pattern to carry product. Flocking may be applied as well or instead of any of these design elements for carrying product. The roller 30 is adapted to move, for example as illustrated by arc 32, as the applicator portion is moved across a portion of the user's body, such as the skin, to apply product that is received from the underlying wicking agent 28 (see FIG. 3). An applicator insert 34 secures the wheel in place.

FIG. 3 shows an exploded view of the applicator. The cap 10 includes an optional cap insert 12, which may be glued, screwed or otherwise affixed to the cap body 14. The cap insert 12 may be in the form of a brand logo or other decorative design.

The body 20 includes the roller 30, again depicted as a wheel. The roller 30 is secured in place to the applicator insert 34, which may have a receiver 38, such as a recess, pocket, groove, slot, etc., for the roller 30. The receiver 38 is configured to hold the roller 30 at the end of the applicator insert 34 while allowing the roller 30 to roll or rotate. The roller 30 may have integrated therein or attached thereto a pin 31 for being received by the applicator insert 34, or a separate pin may be provided. If the roller 30 is a ball, then the receiver 38 may include a collar, lip, ridge, or other structure to secure a ball in place while allowing rotation of the ball.

The lower portion of the body 20 includes a base 22 which serves as a reservoir for product. A collar 24 is disposed within an upper opening in the base, with a spring 26 for loading inside the collar. The spring 26 slides over the lower portion of the applicator insert 34, allowing the applicator insert 34 to be axially moveable relative to the collar 24 and base 22.

A wicking agent 28, which may be an elongated piece of absorbent material such as felt, for example, is provided for extending from the interior of the applicator insert 34, adjacent the receiver 38, into the base 22. The wicking agent 28 may be fixed to an inner collar 25 disposed within the collar 24. In other examples, the wicking agent 28 may be fixed to the collar 24 or the base 22. In some examples, the inner collar 25 may be combined with the applicator insert 34 as a single piece. The wicking agent 28 is fixed relative to the base 22 such that applying the cap 10 onto the base 22 or removing the cap 10 from the base 22 does not change the position of the wicking agent 28.

The wicking agent brings product up from the base 22 to the interior of the applicator insert 34. The length of the

wicking agent 28 is such that, when the spring 26 is in an extended state, such as when the cap 10 is removed, the roller 30 is separated from the wicking agent 28. In other examples, the wicking agent may include a product reservoir 27 with an absorbent tip 29. The product reservoir 27 with absorbent tip 29 may be a replaceable cartridge, allowing the applicator to be refillable. For such examples, the replaceable cartridge may extend into the base 22 such that, rather than the base 22 serving as a reservoir for product, it may be a receptacle for the cartridge.

When the cap 10 is applied, it will push the applicator insert 34 toward the base 22 as the cap 10 engages the collar 24. The cap 10 may engage the collar 24 by an interference fit, a snap fit, or by screwing thereon, with the latter two of these configurations providing enhanced control of the engagement of the wicking agent 28 and the roller 30. Ridges 36 on the outer surface of the applicator insert 34 may interact with elements such as ridges on the interior of the cap 10 to depress the applicator insert 34, compressing the spring 26 to a compressed state, relative to the collar 24, bringing the roller 30 into adjacency or contact with the wicking agent 28, applying product to the roller 30 for delivery to the user after the cap 10 is removed. In another example, the inner surface of the cap 10 may be tapered or include tapered elements such that when the cap 10 is pushed onto the tapered applicator insert 34, the cap 10 pushes the applicator insert 34 toward the base 22, placing the roller 30 into contact with the wicking agent 28. The roller 30 is in contact with the wicking agent 28 only when the cap 10 is engaged with the collar 24. Once the cap 10 is removed from the base 22, the spring 26 pushes the applicator insert 34 upwards, separating the roller 30 from the top of the wicking agent 28.

By the above sequence, in some examples, the roller 30 is separated from the wicking agent 28 when the cap 10 is removed, such that the quantity of product that may be delivered or applied without replacing and removing the cap is limited. Once the limited quantity of product that has been loaded onto the roller 30 has been dispensed, the cap must be replaced onto the collar 24 in order for an additional amount of product to be loaded onto the roller 30.

As an alternative, the base 22 may serve as a chamber to receive a replaceable product container. By, for example, removing the collar 24, such a replaceable product container could be accessed, removed, and replaced. In this design, the wicking agent 28 can be integral to the replaceable product container. Alternatively, the wicking agent 28 can be permanently affixed relative to collar 24, such that only the replaceable product container is swapped out.

Each of these non-limiting examples can stand on its own, or can be combined in various permutations or combinations with one or more of the other examples.

The above detailed description includes references to the accompanying drawings, which form a part of the detailed description. The drawings show, by way of illustration, specific embodiments in which the invention can be practiced. These embodiments are also referred to herein as "examples." Such examples can include elements in addition to those shown or described. However, the present inventors also contemplate examples in which only those elements shown or described are provided. Moreover, the present inventors also contemplate examples using any combination or permutation of those elements shown or described (or one or more aspects thereof), either with respect to a particular example (or one or more aspects thereof), or with respect to other examples (or one or more aspects thereof) shown or described herein.

5

In the event of inconsistent usages between this document and any documents so incorporated by reference, the usage in this document controls.

In this document, the terms “a” or “an” are used, as is common in patent documents, to include one or more than one, independent of any other instances or usages of “at least one” or “one or more.” Moreover, in the following claims, the terms “first,” “second,” and “third,” etc. are used merely as labels, and are not intended to impose numerical requirements on their objects.

The above description is intended to be illustrative, and not restrictive. For example, the above-described examples (or one or more aspects thereof) may be used in combination with each other. Other embodiments can be used, such as by one of ordinary skill in the art upon reviewing the above description.

The Abstract is provided to comply with 37 C.F.R. § 1.72(b), to allow the reader to quickly ascertain the nature of the technical disclosure. It is submitted with the understanding that it will not be used to interpret or limit the scope or meaning of the claims.

Also, in the above Detailed Description, various features may be grouped together to streamline the disclosure. This should not be interpreted as intending that an unclaimed disclosed feature is essential to any claim. Rather, inventive subject matter may lie in less than all features of a particular disclosed embodiment. Thus, the following claims are hereby incorporated into the Detailed Description as examples or embodiments, with each claim standing on its own as a separate embodiment, and it is contemplated that such embodiments can be combined with each other in various combinations or permutations. The scope of the invention should be determined with reference to the appended claims, along with the full scope of equivalents to which such claims are entitled.

The claimed invention is:

1. An applicator for a cosmetic product comprising:
a cap; and
a body, the body comprising:
a roller;
an applicator insert to hold the roller;
a collar configured for mating with the cap;
a spring coupling the applicator insert to the collar;
a portion for holding product; and
a wicking agent;
wherein the roller, applicator insert, collar, spring, portion for holding product, and wicking agent are sized and configured to define:
a first configuration when the cap is applied and engaged to the collar in which the spring is in a compressed state such that the applicator insert is moved to a first juxtaposition and the roller is brought adjacent to or in contact with the wicking agent to deliver product to the roller; and
a second configuration when the cap is not applied in which the spring is in an extended state such that the applicator insert is moved to a second juxtaposition and the roller is separated from the wicking agent.
2. The applicator of claim 1 wherein, in the second configuration, the roller being separated from the wicking agent limits a quantity of product that may be applied without replacing the cap and effecting the first configuration.
3. The applicator of claim 1, wherein the roller is a ball.
4. The applicator of claim 3, wherein the applicator insert includes a recess configured to receive the ball, and a ridge

6

configured to retain the ball within the recess, the recess and ridge configured to retain the ball while allowing the ball to rotate freely.

5. The applicator of claim 1, wherein the roller is a wheel.
6. The applicator of claim 5, wherein the applicator insert includes a slot configured to receive the wheel, and a pin configured to retain the wheel within the slot while allowing the wheel to rotate freely.
7. An applicator for a cosmetic product comprising:
a reservoir for holding the cosmetic product;
a collar disposed with an opening of the reservoir;
a spring disposed within the collar;
an applicator insert having a first end disposed within the spring and extending into the collar;
a roller movably fixed to a second end of the applicator insert;
an elongate wicking agent disposed within the reservoir and extending through the collar, the spring, and into the applicator insert; and
a cap configured for mating with the collar, wherein the reservoir, collar, spring, applicator insert, roller, wicking agent, and cap are configured such that:
when the cap is engaged with the collar, the cap moves the applicator insert toward the reservoir, thereby compressing the spring and moving the roller into contact with the wicking agent, allowing the cosmetic product to move from the reservoir, through the wicking agent, and into contact with the roller;
and
when the cap is removed from the collar, the spring relaxes into an extended position, moving the applicator insert away from the reservoir and moving the roller out of contact with the wicking agent.
8. The applicator of claim 7, wherein the roller is configured to dispense a limited amount of the cosmetic product as the roller is moved against a surface, wherein the limited amount is limited to product in contact with the roller when the cap was removed.
9. The applicator of claim 8, wherein the roller is configured to receive an additional amount of cosmetic product when the cap is engaged with the collar, moving the roller into contact with the wicking agent.
10. The applicator of claim 7, wherein the cap has internal ridges that engage ridges on the applicator insert.
11. The applicator of claim 7, wherein the wicking agent is fixed relative to the reservoir.
12. The applicator of claim 7, wherein the roller is a ball.
13. The applicator of claim 7, wherein the roller is a wheel.
14. The applicator of claim 7, wherein the roller is absorbent.
15. The applicator of claim 7, wherein the roller is non-absorbent.
16. The applicator of claim 7, wherein the roller includes one or more dimples in a surface thereof.
17. The applicator of claim 7, wherein the roller includes a flocking material on a surface thereof.
18. A method of applying a cosmetic product, comprising:
loading cosmetic product onto a roller by placing a cap onto a collar of a cosmetic container thereby engaging the roller with a wicking agent, the cosmetic container including:
a reservoir for holding the cosmetic product;
the collar disposed with an opening of the reservoir;
a spring disposed within the collar;
an applicator insert having a first end disposed within the spring and extending into the collar;

the roller movably fixed to a second end of the applicator insert;
the wicking agent disposed within the reservoir and extending through the collar, the spring, and into the applicator insert; and

5

the cap configured for mating with the collar;
removing the cap thereby limiting an amount of the cosmetic product loaded onto the roller; and
dispensing the limited amount of cosmetic product by

10

rolling the roller onto a user's skin.

19. The method of claim **18**, wherein dispensing the limited amount of cosmetic product includes rolling the roller onto skin until the limited amount of product is dispensed, the method further comprising replacing the cap onto the collar to load a second amount of product onto the ¹⁵ roller.

20. The method of claim **19**, wherein after replacing the cap, the method further comprises removing the cap and dispensing the second amount of product.
